UNITED STATES PATENT OFFICE.

ANDREW McCANN, OF NORTHBEND, WASHINGTON.

AUTOMATIC-BALANCE BRAKE.

1,330,641.

Specification of Letters Patent. Patented Feb. 10, 1920.

Application filed September 19, 1918. Serial No. 254,727.

To all whom it may concern:

Be it known that I, ANDREW McCANN, a citizen of the United States, and a resident of Northbend, in the county of King 5 and State of Washington, have invented a new and Improved Automatic-Balance Brake, of which the following is a full, clear, and exact description.

This invention relates to vehicle brakes 10 and particularly to an automatic balance brake mechanism which acts to avoid uneven brake application so as to obviate skidding and other difficulties in slippery traffic as well as to promote even wear and 15 thus increase the life as well as the effectiveness of the brakes.

A further object of the invention is the provision of an arrangement by which the balanced action of the brakes will be automatic 20 and whereby the same requires minimum attention and with practically no adjustment beyond that occasioned by ordinary wear.

A still further object of the invention 25 is to provide a construction in which there will be no dragging of the brakes and each of the wheels will be caused to act evenly as the wheel resistance of the road is automatically balanced when the brake is applied.

In the accompanying drawings:

Figure 1 is a top plan view of a brake mechanism embodying the invention, the same being shown applied.

Fig. 2 is a detail sectional view of an actuating sliding pedal and its frame, same disclosing certain features of the invention.

Fig. 3 is a front elevation of the brake mechanism associated with one of the wheels 40 of the vehicle shown in Fig. 1.

Fig. 4 is a side view of the mechanism shown in Fig. 3, part of the upper casing being broken away for better illustrating certain features of the invention.

Referring to the accompanying drawings 45 by numerals 10 indicates a brake drum rigidly secured in any desired manner to the respective wheels 34 and 35, there being one housing for each wheel and identical mechanism associated therewith so that the description of one housing and one set of

mechanism will equally apply to both. This mechanism is shown in detail in Figs. 3 and 4 to which special reference is made. As-

50 associated with the drum 10 is a flange 11 rigidly secured to the axle casing 11', said

flange of course being stationary and fitted loosely in the drum 10 shown at the bottom of Fig. 3 so that the drum 10 may rotate with the wheel freely. Any suitable form 60 of emergency brake may be used and arranged interiorly of the drum 10, said emergency brake mechanism forming no part of the present invention, in Fig. 4 a lever 8 and operating rod 9 being shown. Arranged at the upper part of the drum 10 is a casing 12 which is rigidly secured to the flange 11 by any suitable means, as for instance rivets as shown in Fig. 4, said casing having an inwardly bent portion 14 through 70 which suitable hook bolts 14' extend, said hook bolts interlocking with one end of the respective retractile coil springs 13 and 13'. The opposite ends of these springs are connected to the flexible cables 21, which cables 75 in turn pass through suitable openings in the casing 12 and over guiding pulleys 22 so that the opposite ends may be rigidly secured in any suitable manner to the brackets 20 of the upper section 15 of the brake 80 band. A pair of coils 46 are arranged in casing 12 and act against said casing as hereinafter fully described, said springs being connected at one end of the casing and at the opposite end to a connecting bar or 85 shoe 47 so that when spring 13 expands to a certain extent the same will engage the bar 47 so that the springs 46 will begin to act.

The brake drum 10 connected with the 90 wheel is provided with a brake band formed in two parts, namely an upper semi-cylindrical section 15 having brackets 20 as shown in Fig. 4 and a lower semi-cylindrical section 16 having brackets 20 constructed 95 similar to the brackets of section 15. The sections are so proportioned that the brackets 20 of the respective sections will be spaced a short distance apart, said sections 15 and 16 being of course on opposite sides of the 100 axle 17 and the casing 11'. Each of these sections carries its respective section 19 of the brake lining, so that when the sections are forced toward the drum 10 a gripping action will be provided, said action being 105 in proportion to the movement of said sections.

The respective brackets 20 are threaded, the opposing brackets being provided with right and left hand threads respectively for 110 receiving the respective screw shafts 23 which are provided with right and left hand

threads, so that upon a rotation of these shafts sections 15 and 16 will be moved toward each other or away from each other so as to apply or disengage the brake band. 5 Adjacent the lower ends of the respective screw shafts 23 spur gears 31 are provided, said gears being rigidly secured to the respective shafts 23 and positioned to engage the rack face of the rack bars 32, said rack 10 bars extending across the face of flange 11 and engaging simultaneously both of the gears 31 so that both gears will be operated at the same time and to the same extent, whereby the respective screw shafts will be 15 moved so that the respective pairs of brackets 20 will be simultaneously spread or brought toward each other. It will be evident that when the rack bars 32 are moved in one direction the screws 23 will be moved 20 for causing the brake band to be applied and when moved in the opposite direction will cause the brake band to be disengaged.

A pair of supporting bars 24 and 25 are pivotally connected at 26 to the flange 11, 25 said fulcrum 26 being arranged at the centers of the respective bars. These supporting bars are provided with horizontally extending extensions 27 and 28 at each end, said extensions having apertures through 30 which the screw shafts 23 extend, whereby the lower set of projections 28 act as supports for the shafts 23 and associate parts. The extensions 28 at each end of the respective bars 24 and 25 are connected by 35 uprights 29, said connections being pivotal and of any desired structure, as for instance an ordinary bolt extending through an aperture in the uprights and threaded into the respective extensions 28. Each of the uprights 29 is provided near its lower end with a recess or groove 30 as shown in Fig. 3 for accommodating the rear face of the rack bar 32 whereby the same is properly supported as it slides back and forth. In 40 addition to this support the rack bar 32 is provided with an overlapping flange 32' which rests on the respective spur gears 31.

Each of the rack bars 32 is provided with a spring 36 which is secured at one end to 50 the respective rack bars as shown more particularly in Fig. 1 and at the opposite end to the lower section 16 of the brake bands. These springs act to move the rack bar rearwardly so as to release the brake band 55 when the pedal 45 and associate parts are released. In addition these springs act to cause the balancing of the braking effect as hereinafter fully described. The respective rack bars 32 are pivotally connected at 60 37 to a transverse brake beam 38 which is provided with a yoke 39 at a central point, said yoke being pivotally connected at 40 to a forwardly extending connecting rod 41. The connecting rod 41 is pivotally connected 65 at 42 to a slide block 43 carried by the

parallel guide rods 44 supported in any desired manner on the vehicle. The pedal 45 is preferably pivotally connected to the slide block 43 and is positioned so as to be readily operable from the operating station of the vehicle, whereby whenever the operator desires to apply the brake he may press upon the pedal 45 and move the block 43 forwardly. This will pull on the rod 41 and also on the brake beam 38 so as to cause 70 a forward motion of the respective rack bars 32. This forward motion of the rack bars 32 will rotate the respective spur gears 31 and move the sections 15 and 16 adjacent each wheel toward the drum 10 connected 75 to each wheel for producing a braking action, the amount of movement of the sections 15 and 16 being in proportion to the amount of movement of the pedal 45. When it is desired to release the brake mechanism 80 the operator removes his foot from the pedal 45 and springs 36 return the respective parts to their former position and will cause a positive release or unclutching of the brake band. 85

By reason of the pivotal connections at 90 37 and pivotal connections at 40 there will be an automatic balancing of the strain and consequently an automatic balancing of the braking action. In addition to this automatic distribution of the strain and consequent braking action the arrangement of the spring 36, rack bars and associate parts will produce an additional automatic balancing of the braking action. For instance 95 100 if one of the brake bands does not grip entirely properly for any reason, as for instance by reason of having too much oil thereon the opposite band will be rotated somewhat by reason of its engagement with 105 the drum 10 as there is more tension on that particular wheel. This rotation of the brake band will bring the particular spring 36 connected with the above mentioned 110 brake band under tension and said extra tension will cause the rack bar 32 connected with spring 36 to move rearwardly and consequently cause the spur gears 31 and the screw shafts 23 to rotate sufficiently to release the brake bands associated therewith 115 so that additional strain will be brought on the brake band which is slipping. In this way the respective brake bands will have applied thereto a sufficient strain to cause the respective wheels to be equalized or 120 balanced in their resistance. In this way the respective brake shoes are balanced, but the emergency brake connected with lever 8 and rod 9 is not balanced, but is operated the same as is usual on cars only from the bottom instead of half way up. The balancing of the emergency brake is not necessary, as the service brake will hold all that the road 125 conditions will allow when the streets are slippery. 130

It will be noted that when the streets are slippery, or for some reason the automatic balancing of the brake is necessary and the sections 15 and 16 begin to rotate cable 21 will begin to move and bring the spring 13 under tension, if the movement is sufficient said spring will engage bar 47 and check further movement by reason of the action of spring 46, said checking however being yielding in order to prevent a sudden stop of the movement. When the vehicle is moving in an opposite direction the same action takes place, spring 13' will act, but as the momentum of the vehicle is less than in the forward movement the springs 46 and associate parts are not necessary. The control spring 36 attached to the lower quarter of the band, namely section 16, and the other end attached to the rack 32 are under considerable tension when the brakes are set and the strain is equally divided until one wheel offers more resistance than the other. When this occurs the wheel with the least resistance naturally gives way, the tension of the springs on top of the drum and the springs on the brake band and rack of the other wheel is increased and the result is the slackening of one and the automatically tightening of the other until a balance is secured.

30 I claim as my invention:

1. A vehicle brake, comprising a two section band, means connecting said sections to move them toward and away from each other, a pair of springs anchored at one end and flexibly connected at their opposite ends to one brake band section, and normally inactive tension means in the path of movement of one of the springs for the purpose described.

40 2. A vehicle brake comprising a brake band in upper and lower sections having opposing end pieces, means connecting said end pieces to move said sections toward and away from one another, and a pair

45 of springs anchored at one end and

flexibly connected at their opposite ends to the opposite end pieces of the upper brake band section, and normally inactive tension means in the path of movement of one of the springs for the purpose described. 50

3. A brake comprising a brake housing, a pair of supporting arms fulcrumed adjacent their center above and below the center of said housing, upper and lower brake band sections having opposing end extensions 55 provided with threaded openings, screw shafts having oppositely threaded portions extending through the said threaded openings and having their ends journaled in the ends of said supporting arms and means to 60 simultaneously rotate said screw shafts, as described.

4. A brake comprising a brake housing, a pair of supporting arms fulcrumed adjacent their centers above and below the center of said housing, upper and lower brake band sections having opposing end extensions 65 provided with threaded openings, screw shafts having oppositely-threaded portions and having their ends journaled in 70 the ends of the said supporting arms, gears carried by the said screw shafts, and sliding rack bars engaging said gears for rotating the same and said screw shafts.

5. A brake comprising a brake housing, 75 a pair of supporting arms fulcrumed adjacent their centers above and below the center of said housing, upper and lower brake band sections having opposing end extensions 80 provided with threaded openings, screw shafts having oppositely-threaded portions and having their ends journaled in the ends of the said supporting arms, gears carried by the said screw shafts, sliding rack bars engaging said gears for rotating the 85 same and said screw shafts, and upright guide members connecting the ends of said supporting arms, and in which the said rack bars have guided movement, as described.

ANDREW McCANN.
